BELL RINGING DEVICE FOR ELECTRIC TOY TRAINS

Albert N. Peffers, Ossining, N. Y.

Application May 16, 1938, Serial No. 208,276

2 Claims. (Cl. 246—174)

This invention relates to bell ringing devices for electric toy trains and has for an object to provide an electro-magnet supplied with current by wayside apparatus through collecting means on the train for ringing a miniature bell on an electric engine at certain points in the track, as for example, on a straight stretch of track just preceding a curve.

A further object is to provide a device of this character which will be formed of a few strong simple and durable parts, which will be inexpensive to manufacture and install and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a side elevation of an electric engine equipped with a bell ringing device constructed in accordance with the invention.

Figure 2 is a cross sectional view of the engine taken on the line 2—2 of Figure 1 and showing the contact shoes for the electro-magnet in rear elevation.

Figure 3 is a fragmentary plan view of a section of the track showing the conductor strip for supplying current from a transformer to the electro-magnet when the control switch is closed.

Figure 4 is a longitudinal sectional view taken on the line 4—4 of Figure 3 showing the flush joint between two sections of the conductor strip.

Figure 5 is a perspective view of one end of a conductor bar section.

Figure 6 is a perspective view of the end of an adjacent conductor bar section to be joined to the section shown in Figure 5.

Figure 7 is a plan view of the track and showing adjacent sections disconnected, and also showing the transformer and the control switch for the bell ringing electro-magnet.

Referring now to the drawings in which like characters of reference designate similar parts in the various views, 10 designates the engine of a toy electric train, the same running on metal track rails 11 which are grounded to metal ties 12, there being a third rail 13 connected by a wire 14 to a transformer 15 for supplying current to run the train. One of the track rails is connected by

a wire 16 to the transformer. These wayside parts for supplying current are conventional.

In carrying out the invention a miniature bell 17 is mounted to rock on a shaft 18 which is journaled in sides of an arched bracket 19 mounted on top of the engine near the front thereof. The bell is provided with a crank lever 20 through the medium of which the bell may be rocked to permit the clapper 21 to impinge against the bell and simulate the ringing of an actual locomotive bell.

A cable 22 is connected to the lever 20 and is trained through a guide eye 23 formed in the upper end of a bracket arm 24 which is secured to the top of the locomotive. From thence the cable is trained over a guide pulley 25 carried by a bracket 26 which is secured to the top of the locomotive cab and thence is directed downwardly into the cab through an opening 27.

A lever 28 is connected at the forward end to the rear end of the cable and at the rear end is provided with a bearing sleeve 29 which is journaled on a shaft 30 extending transversely of the locomotive cab. The sleeve is insulated from the shaft through the medium of a sleeve 31 of insulating material, best shown in Figure 2. A helical spring 32 is connected at one end to the top of the cab through the medium of a bushing 23 and is secured at the lower end to the lever 28. An armature 34 is secured to the underneath face of the lever in advance of the spring and is adapted to be attracted by the core of an electro-magnet 35 to pull the cable and rock the bell in one direction while the spring 32 moves the lever to slack the cable and permit the bell to rock in the opposite direction when the electro-magnet is deenergized.

An electro-magnet 35 is mounted upon an annular bracket arm 36 secured transversely to the cab as shown in Figure 2 and the circuit wires 37 of the coil are connected to respective collecting devices comprising spring metal shoes 38 which are secured to a bracket arm 39 secured to the bottom of the cab and formed of insulating material. One of the shoes is longer than the other shoe and is adapted to have wiping contact with the metal ties 12 to break the circuit to the electro-magnet as the shoe crosses the gap between two adjacent ties. The other shoe is adapted to have rubbing contact with a conductor bar 40 which is mounted on a strip 41 of insulating material secured to the ties between one of the track rails 11 and the third rail 13, as best shown in Figures 2 and 3.

A switch 42 is provided with a movable switch contact 43 and a fixed switch contact 44, the

former being connected by a wire 45 to one side of the transformer and the latter being connected by a wire 46 to the metal conductor bar 40.

5 The track rails and the third rail of conventional toy trains are formed in sections, one section being provided with coupling pins 47 receivable in the hollow heads of the rails of the adjacent sections. Likewise the bar 40 is formed in sections, the insulating strip 41 having an interfitting tongue 48 and groove 49 at the joint between the sections, and the conductor bar 40 having an interfitting tongue 50 and groove 51 to provide a flush joint at the meeting ends 15 of the sections as best shown in Figures 4, 5 and 6.

In operation when the movable switch arm 43 is moved to circuit closing position, current will be supplied to the metal contact strip 40 and when the long shoe 38 is in contact with a metal tie, a circuit may be traced from the transformer, through the wire 45, movable contact 43 of the switch 42, fixed contact 44, wire 45, metal conductor bar 40, short shoe 38, conductor bar 37, 25 coil of the electro-magnet 35 and through the other wire 37 to the tie, track rail 11 and wire 16 to the transformer. When this circuit is thus closed the armature 34 will be attracted by the core of the electro-magnet and the lever 28 will 30 be swung downward to pull the cable 22 and rock the bell in one direction. As soon as the short shoe leaves the tie the circuit will be broken and the spring 32 will immediately pull the lever upward to slack off the cable 22 and 35 permit the bell to swing in the opposite direction. Thus an audible bell ringing to simulate actual bell ringing on a locomotive is effected, while at the same time movement of the bell cable 22 is visible to simulate movement of the 40 pulling of an actual locomotive bell cable.

From the above description it is thought that the construction and operation of the invention will be fully understood without further explanation.

What is claimed is:

1. The combination with a toy electric track and electric locomotive thereon, of a contact bar disposed adjacent to the track, means for supplying an electric current to the bar, said track having rails and ties forming a return circuit 10 for the current, metal brushes carried by and insulated from the locomotive, one brush having wiping contact with said bar and the other brush having wiping contact with said ties to interrupt the current, an electro-magnet on the 15 locomotive electrically connected to said brushes, a bell on the locomotive, a spring controlled lever connected to the bell, and an armature for rocking the lever to ring the bell when the electro-magnet is energized. 20

2. The combination with an electric toy track and locomotive thereon, of a bell pivotally mounted on the locomotive and simulating an actual locomotive bell, a cable for ringing the bell, electro-magnetic means for pulling the 25 cable in one direction, a spring opposing said means for slackening the cable to permit return of the bell to initial position, said track having rails and ties forming a circuit for said electro-magnetic means, a wayside source of current 30 supply for the circuit, a bar forming a conductor in said circuit and located longitudinally of the track at a predetermined point thereof, and collecting brushes on the locomotive electrically connected to said electro-magnetic means and 35 engaging said bar conductor and said ties, said brushes intermittently interrupting the circuit as the locomotive travels upon the track.

ALBERT N. PEFFERS. 40
